Design U.S. Appl. No. 29/659,650, filed Aug. 10, 2018, entitled "Pattern", first named inventor: Marc Zemel.

Primary Examiner — Joseph Kukella*Assistant Examiner* — Darryl J Dardenne(74) *Attorney, Agent, or Firm* — Carter, DeLuca & Farrell LLP(57) **CLAIM**

The ornamental design for a topper set, as shown and described.

DESCRIPTION

FIG. 1 is a top perspective view of a topper set illustrating its individual elements together in accordance with the present design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a perspective view of the topper set illustrating its individual elements separated in accordance with the present design.

The broken lines shown in the drawings illustrate portions of the topper set that form no part of the claimed design.

1 Claim, 6 Drawing Sheets---
